UNITED STATES PATENT OFFICE.

GEORGE RAVENSHEAR, OF WEST EALING, ENGLAND.

TARGET.

1,223,290.

Specification of Letters Patent.

Patented Apr. 17, 1917.

Application filed August 24, 1915. Serial No. 47,106.

To all whom it may concern:

Be it known that I, GEORGE RAVENSHEAR, a subject of the King of the United Kingdom of Great Britain and Ireland, residing 5 at 39 Broadway, West Ealing, Middlesex, England, surveyor, have invented a new and useful Target, of which the following is a specification.

This invention relates to targets for use 10 in miniature shooting ranges and the essential features of the invention consist in mathematically proportioning or calculating the size of the figure on the target so that when viewed at a comparatively short range, 15 the figure will appear to the marksman as if it were seen by him in real life at a much greater range and in separating the vital parts of the figure on the target with inclosing lines so that said figure is divided 20 into sections representing the value of the hits.

As an example of carrying my invention into practice, a target for use in a miniature shooting gallery having a range of 25 yards, 25 and intended to represent a human figure as if seen in real life at a distance of 400 yards should have said figure of a height of 4 $\frac{3}{4}$ inches.

In order that my invention may be readily 30 understood and carried into effect I will now proceed to describe the same fully for which purpose reference should be had to the accompanying drawing which shows a target embodying my invention.

In that embodiment of my invention 35 illustrated the target A which may be of cardboard or any other suitable material bears the representation of a soldier the vital or important part of the figure being 40 separated from the remainder by inclosing lines B and/or by broken or dotted lines C said lines being either printed on the target or marked by a wire embedded or impressed in the substance of the target or otherwise 45 so placed as to allow of distinguishing between narrow escapes disabling hits or dangerous and probably fatal or mortal hits.

The different parts have different scoring 50 values attached to same thus for example the parts C which inclose the vital parts

and organs of a human being may have a value of ten assigned thereto as a hit there would probably kill outright. A hit on the other portion inclosed by the line B may 55 have a value of five assigned to it as a bullet in this part would badly wound and incapacitate. A hit on other parts of the figure not inclosed by lines B or C may have a value of two assigned to the same. 60

The figures on the targets may be in any color or combination of colors or in half tone as may be found necessary or desirable.

By the use of my improved target representing persons, animals or objects at specified ranges the recruit or marksman is also taught to recognize intuitively the correct range of the distant person, animal or object that he is shooting at and marksmen can also be given special instruction in fixing 70 ranges by finger measurements against the targets.

What I claim is:—

1. A target for miniature and other ranges comprising the representation of an object 75 reproduced upon a surface the size of said object being mathematically proportioned so that when viewed at a comparatively short range said object will appear to the marksman as if seen by him in real life at 80 a much greater range and a contrasting line on said object inclosing specific parts thereof for the purpose of allotting to them higher scoring values.

2. A target for miniature and other ranges 85 comprising the representation of an object reproduced upon a surface the size of said object being mathematically proportioned so that when viewed at a comparatively short range said object will appear to the 90 marksman as if seen by him in real life at a much greater range and a contrasting line of wire embedded in said surface inclosing specific parts for the purpose of allotting to them higher scoring values. 95

In testimony whereof I affix my signature in the presence of two witnesses.

GEORGE RAVENSHEAR.

Witnesses:

CHAS. MORSTATT,
A. E. WHITE.
